ATTORNEY

UNITED STATES PATENT OFFICE

99,774

DESIGN FOR A BOWLING ALLEY SETTEE

Faber Birren, Chicago, Ill., assignor to The Brunswick-Balke-Collender Company, Chicago, Ill., a corporation of Delaware

Application April 10, 1936, Serial No. 62,053

Term of patent 3½ years

To all whom it may concern:

Be it known that I, Faber Birren, a citizen of the United States, residing in Chicago, in the county of Cook, State of Illinois, have invented a new, original, and ornamental Design for a Bowling Alley Settee, of which the following is a specification, reference being had to the accompanying drawing, forming a part thereof.

In the drawing—

The figure is a perspective view of a bowling alley settee showing my new design.

I claim:

The ornamental design for a bowling alley settee as shown.

FABER BIRREN.
